UNITED STATES PATENT OFFICE.

JOSEF LEITER, OF VIENNA, AUSTRIA, ASSIGNOR TO FERDINAND G. OTTO
AND JOHN REYNDERS, OF NEW YORK, N. Y.

IMPROVEMENT IN HYPODERMIC SYRINGES.

Specification forming part of Letters Patent No. 145,217, dated December 2, 1873; application filed November 1, 1873.

To all whom it may concern:

Be it known that I, JOSEF LEITER, of Vienna, Austria, have invented an Improved Hypodermic Syringe, of which the following is a specification:

Figure 1 is a longitudinal section, on an enlarged scale, of the lancet-tube of my improved hypodermic syringe. Fig. 2 is a side view, also on an enlarged scale, of the syringe. Fig. 3 is a sectional side view on an enlarged scale, showing the syringe applied to the bottle or receptacle from which the liquid is drawn; and Fig. 4, a perspective view of the case within which the syringe, bottle, and lancet-tube are placed.

Similar letters of reference indicate corresponding parts in all the figures.

This invention has for its object to improve the construction of the lancet-tubes of hypodermic syringes, and of the syringe cylinder, that the plunger may be readily introduced therein, and the caps fitted upon it without difficulty and with perfect security. The invention consists in enlarging the bore of the cylinders conically at the ends, so that the introduction of the plunger will be greatly facilitated.

Heretofore the syringe-cylinders were always made of equal internal diameter throughout, and, as the plunger has to fit tightly therein, its application to the cylinder, when once removed, was a matter of exceeding difficulty, which is avoided by my improved construction. The same feature of enlarged cylinder ends permits, also, the use of conical or plain cylindrical plugs, whereby the cylinder ends are closed, which plugs thus perform their function without being provided with screw-threads, and will always completely fit and secure the cylinder and the attachments thereto.

In the drawing, A represents the cylinder of the syringe. B is its plunger; C, the graduated plunger-rod; D, the plunger-handle; E, the lower tubular plug, through which the plunger-rod enters the cylinder A; F, the tubular cap, to which the lancet-tube G is secured; H, a double plug for connecting the cylinder A with the bottle I, from which the liquid is drawn into the cylinder; and J, the tubular

plug for the upper end of the cylinder A, and for the reception either of the plug F or H. The lancet-tube G is made of steel, of the ordinary form and size, the size hardly ever exceeding that of a sewing-needle. The channel or bore of the tube G is, therefore, exceedingly small; still I line the interior of this bore with a coating, a, of platinum, which is the metal best adapted for protecting steel against the injurious influences of liquids that may be forced through the lancet-tube. The outside of the tube G is covered and protected by a coating of nickel, b, whereby the steel is protected against the influences of the atmosphere, which nickel covering also protects the point d of the lancet, as is more fully indicated in Fig. 2. The tube G is screwed into, or otherwise rigidly connected with, the plug F, said plug being slightly conical, as shown, or cylindrical, and of such size as to conveniently fit the plug J, which is placed upon the upper end of the tube A. The tube A, which is made of hard rubber, glass, or equivalent material, has its cylindrical bore slightly enlarged toward the ends, so that the bore will flare outward, as indicated in Fig. 3. That portion of the tubular plug J which enters the bore of the cylinder A may also be slightly conical, so as to fit the flaring part of the bore of A in the manner shown, or may as well be cylindrical. The plug F, when the syringe is in position for use, as in Fig. 2, is finally introduced within the cylindrical, or partly conical, bore of the plug J. The other or lower end of the cylinder A is also enlarged, the same as the other end, and receives the plug E, which has a corresponding conical or cylindrical form where it enters the same. These plugs J and E can thus be readily withdrawn from the cylinder A, and will, when applied, properly and tightly fit the same.

By this construction, the necessity of having screw-threads on the internal bore, and on the said plugs E and J, is dispensed with, and fully as firm and more convenient a fastening in every respect is produced. The chief object, however, of having the bore of the cylinder at the lower end conical is, that the intro-

duction of the plunger B is thereby greatly facilitated, as above already stated.

The bottle I, from which the liquid is to be drawn, has the double plug H fitted into its mouth, the projecting end e of said plug being of the same size as the plug F, so that it may be introduced into the bore of J whenever the cylinder A is to be connected with the bottle I. When the bottle is disconnected, a cap, L, is placed over the part e of the plug H. M is the case, within which the syringe and all its appurtenances are to be packed. In the lid or bottom of this case is secured a cushion or block, N, which has as many grooves formed on its face longitudinally as there are to be lanceet-tubes packed in the case, and which is embraced, at one or more places, by a cord, f, or equivalent yielding substance, such cord extending transversely over the aforementioned groove or grooves.

When the lanceet-point is to be fitted into the case it is merely inserted into one of the grooves beneath the cross-bands f f, and firmly held in place thereby, and not apt to be injured during the process of introduction or removal.

I claim as my invention, and desire to secure by Letters Patent—

1. The cylinder A of a hypodermic syringe, made with the enlarged ends to its bore, substantially as and for the purpose herein shown and described.

2. The combination of the conical plugs J and E, and of the plunger B and conical plug F with the cylinder A of a hypodermic syringe, as described.

JOSEF LEITER.
